FIG 1

FIG 2

MAURICE DUVALET
INVENTOR

Louis Casper
ATTORNEY

UNITED STATES PATENT OFFICE

134,645

DESIGN FOR A PIN OR SIMILAR ARTICLE

Maurice Duvalet, Congers, N. Y.

Application November 2, 1942, Serial No. 108,671

Term of patent 3½ years

To all whom it may concern:

Be it known that I, Maurice Duvalet, a citizen of the United States, residing in Congers, in the county of Rockland and State of New York, have invented a new, original, and ornamental Design for a Pin or Similar Article, of which the following is a specification, reference being had to the accompanying drawing, forming part thereof.

Fig. 1 is an elevational front view of a pin or similar article showing my new design, and

Fig. 2 is an elevational side view thereof.

I claim:

The ornamental design for a pin or similar article, substantially as shown.

MAURICE DUVALET.
